UNITED STATES PATENT OFFICE.

HARRY C. INNES, OF CINCINNATI, OHIO, ASSIGNOR TO THE PHILIP CAREY MANUFACTURING COMPANY, OF LOCKLAND, OHIO, A CORPORATION OF OHIO.

JOINT-STRIP-LAYING DEVICE AND METHOD.

1,255,611.

Specification of Letters Patent.

Patented Feb. 5, 1918.

Application filed July 26, 1917. Serial No. 182,860.

To all whom it may concern:

Be it known that I, HARRY C. INNES, a citizen of the United States, and a resident of Cincinnati, in the county of Hamilton and State of Ohio, have invented certain new and useful Improvements in Joint-Strip-Laying Devices and Methods, of which the following is a specification.

My invention relates to paving, and its object is to provide means for more readily and accurately positioning the joint strips which are used between adjacent sections of paving to compensate for the contraction and expansion of the paving.

15 My invention consists in the combination of parts and in the details of construction and arrangement of parts and in the method as will hereinafter be more fully described and claimed.

20 In the drawing:

Figure 1 is a general perspective view of part of a pavement under construction showing my invention in use;

25 Fig. 2 is a similar view showing a modification of my invention;

Fig. 3 is a partial plan view of the device as shown in Fig. 1 or Fig. 2;

30 Fig. 4 is a vertical cross-section on a plane corresponding to the line 4—4 of Fig. 3; and

Fig. 5 is a detail perspective view showing another modification of my invention.

35 My invention is more especially intended for use in the construction of concrete paving and concrete beds for brick, stone, block or other pavement.

The joint strips used are generally made up of some kind of fibrous or granular material combined with some adhesive material, 40 as for instance, a fibrous material or granular mineral substance combined with bituminous material, the purpose being to provide a strip which is yielding or elastic and must be compressed when the pavement expands and in some measure expand again when the pavement contracts. Such strips are usually provided in lengths of several feet and of width equal to the depth of the pavement and generally from one-fourth to 45 one-half inch thick. Such strips of such width and thickness and in such length and made of such material are somewhat flexible,

and, of course, being thin do not readily stand alone in the vertical position they are to have in the pavement. Consequently, the 55 ordinary methods heretofore employed are attended with considerable trouble, because the joint strips have become bent in shipping and handling and are easily overturned when set in vertical position across the sub-grade even where stakes are driven to hold them up; this being especially liable to happen when the concrete is put in the pavement and flows against the strip. Under such difficulties it often results that the 60 strips, instead of being arranged in a practically straight line end for end across the sub-grade and standing in vertical position, are curved in various directions, their ends do not properly meet and they lean one way. 65 or the other after the concrete has been poured on both sides of the strips. This, of course, is a very unsatisfactory condition; and especially is the leaning of the strip one way or the other highly undesirable because 70 then instead of functioning as a compressible and expandable element to compensate for the expansion and contraction of the paving sections on both sides of it, the strip acts as an incline, which, although a very steep one 75 will often result in one section of the paving tending to ride up over the other one when expansion takes place. This, of course, is 80 very destructive to the pavement.

My invention to overcome these difficulties, 85 as I prefer to construct it, comprises lengths 1 of sheet metal preferably about one-sixteenth inch thick bent to form a relatively very narrow and deep channel which is inverted so that the bottom of the channel 90 forms the top 2 which is preferably substantially semi-circular as this formation of the bottom of the channel is found to better maintain the sides 3 parallel.

This channel is somewhat wider inside 95 than the thickness of the strip 4 that is to be held by it, so that the strip is very readily inserted. As above alluded to, the strips are generally somewhat curved or bent in various directions when they reach the paving site, 100 and these slight curvatures may be depended upon to cause parts 5 of opposite sides of the strip to engage with the inner sides of the channel, as is indicated in Fig. 3. Thus,

sufficient frictional contact of the strip with the insides of the channel will be provided to hold the strip in the channel when it is inverted in the position shown in the drawing.

Near the end of each channel or strip 1, I prefer to cut a slot 6 down through the top of the metal and to fasten a handle 7 to the top of the metal near each slot. Also, as shown on one of the lengths in Fig. 1, there may be plugs 8 to close the slots 6 and these plugs may be fastened by chains 9 to the metals or channels, so as not to be lost when the parts are handled. These plugs are detachable and can be made of such lengths as to fit down upon the top of the joint strip (Fig. 4) so as to further hold the joint strip down upon the sub-grade and prevent its rising due to buoyancy in contact with the fluid concrete, should such contact occur, as in Fig. 2. Also each length may have fixed to one side near one end a cleat 10 which will overlap the end part of the next adjacent length causing them to be properly aligned.

Thus or similarly constructed, the channels or metals 1 are turned over with their open bottoms accessible, and through these bottoms are inserted the joint strips 4 and then the channels are placed in alinement across the sub-grade 11 with their lower edges and the lower edges of the joint strips 4 resting on the sub-grade. Suitable stakes 12 are driven at intervals in the sub-grade against one or both sides of the line of channels to maintain the channels in upright position until the concrete 13 and 14 is poured in on both sides of the line of channels. Where the plugs 8 are provided, these are inserted in the slots 6 to guard against pouring any concrete down inside the channels, as this will tend to hinder withdrawal of the channels from the strips in the succeeding steps of the operation. After the concrete 13 and 14 is poured on both sides of the line of channels, the channels may be lifted out by grasping the handles 7 while pressing on the tops of the joint strips by means of a slender instrument inserted through the slots 6; the plugs 8, of course, being removed for this purpose. The stakes 12 are also pulled out, whereupon the still fluid concrete flows against the joint strips simultaneously on both sides without tilting the strips either way. Thus, the strips are properly positioned in the pavement with the concrete abutting them closely on both sides as is required.

In the modification shown in Fig. 2, the sides 3' of the channels 1' have recesses 15 cut in them at intervals extending up from the bottom edges of the channel sides so that the concrete 13 and 14 is allowed to flow directly against the opposite sides of the joint strips 4 for about the extent of each one of these recesses 15. Thus, the

concrete already hugging the strips closely on both sides of their lower parts at intervals is adapted to hold the strips down when the channels are removed; this effect being added to that of the pressure through the slender instrument inserted through the slot 6.

In the modification shown in Fig. 5, instead of a single strip of metal bent into a channel shape, there are two opposite elongated plates 16 between the upper edge parts of which are bars 17 of approximately square cross-section with rivets 18 passing through the plates 16 and the bars 17. Parts of the bars 17 are omitted near the ends, leaving openings such as the opening 19, for the same purpose as the slots 6 in the preceding examples. The method of operation of this modified construction is the same as in the preceding example, the chief difference being that it is somewhat heavier and more substantial.

It will be understood that other modifications of my invention are possible without departure from the scope and spirit of the following claims:

1. A joint-strip-laying device comprising an inverted channel to contain the strip while paving material is being laid on opposite sides thereof and adapted to be withdrawn after the paving material is laid, each channel having an extension from its end at one side to overlap an adjacent channel whereby said channels are held in alinement.

2. A joint-strip-laying device comprising an inverted channel to contain the strip while paving material is being laid on opposite sides thereof and adapted to be withdrawn after the paving material is laid, and having an opening in its upper part for insertion of an instrument against the top of the strip to hold the strip down when the channel is withdrawn, and a plug fitting in said opening to close it and to hold down the strip while the paving material is being placed on opposite sides of said channel.

3. A joint-strip-laying device comprising an inverted channel to contain the strip while paving material is being laid on opposite sides thereof and adapted to be withdrawn after the paving material is laid, said channel having recesses in its sides up from the lower edges of said sides at intervals therealong whereby the paving material may come into direct contact with opposite sides of the joint strip as held in said channel.

4. A joint-strip-laying device comprising an inverted channel to contain the strip while paving material is being laid on opposite sides thereof and adapted to be withdrawn after the paving material is laid, said channel having recesses in its sides up from the lower edges of said sides at inter-

vals therealong whereby the paving material may come into direct contact with opposite sides of the joint strip as held in said channel, and having an opening in its upper 5 part for insertion of an instrument against the top of the strip to hold the strip down when the channel is withdrawn.

5. A joint-strip-laying device comprising side elements to flank the joint strip and 10 hold it in upright position while paving material is placed on both sides of said device, and having a closed top to prevent entrance of the paving material around the strip between said side elements when the paving 15 material is being laid, and having an opening in said top for the insertion of an instrument against the top of the joint strip to hold said strip down when the device is withdrawn, and a plug for closing said open-

ing and holding the strip down while said 20 paving material is being laid.

6. The method of laying joint strips in concrete or similar pavements of initial fluid condition which consists in loosely flanking said strip by withdrawable means, placing 25 said strip and said means in the position it is to occupy in the pavement with said means in position for being withdrawn upward, then pouring the concrete or the like on opposite sides of said means, and then withdrawing said means and allowing said concrete or the like to flow directly against said joint strip.
